United States Patent Office.

SHERMAN SMITH, OF PRESQUE ISLE, MAINE.

Letters Patent No. 65,701, dated June 11, 1867.

IMPROVED WINDOW-SASH FASTENER.

The Schedule referred to in these Letters Patent and making part of the same.

TO ALL WHOM IT MAY CONCERN:

Be it known that I, SHERMAN SMITH, of Presque Isle, in the county of Aroostook, and State of Maine, have invented a new and useful Improvement in Window-Sash Fasteners and Operators; and I do hereby declare that the following is a full, clear, and exact description thereof, which will enable others skilled in the art to make and use the same, reference being had to the accompanying drawings, forming part of this specification, in which—

Figure 1 is an outside view of a window provided with my invention.

Figure 2, a vertical section taken in the line *x x*, fig. 1.

Figure 3, an inside view of the window.

Figure 4, a horizontal section taken in the line *y y*, fig. 1.

Similar letters of reference indicate like parts.

This invention has for its object to provide a convenient device for raising and lowering the upper and lower sash of a window, and fastening either of them in any desired position as regards height.

A is a window-frame, in which are fitted the upper and lower sashes *B B'* in the usual way. A long, thin, and narrow metal bar, *a a*, is fastened at its upper end to the middle of the window-frame on the inside at its upper part, and passes down inside of the lower sash *B'*. A straight rack, *c c*, is fastened at its upper end to the top of the upper sash *B*, and lies close on the inside of the bar *a a*, with which it corresponds in size and length. The lower ends of the bar *a a* and rack *c c* are both enclosed by a loop or band, *b*. By this arrangement the upper sash *B* can be lowered, when the rack *c c* will slide through the band *b*, and by means of a thumb-screw, *d*, that passes through the band *b* and the rod *a a* and bears against the rack, it may be held at any point, and thus the upper sash may be fastened at any height in the window when lowered. The lower sash *B'* has a metal plate, *e*, screwed to the upper part on the inner side of the window, to which plate is pivoted on the outer side of the sash a toothed wheel, *g*, the teeth of which take in the teeth of the rack *c c*, and when it is turned by a crank-key, *h*, raises or lowers the sash *B'* to any desired point, where it is held by a catch-rod, *i*, that is pivoted at one end to the top of the sash, and locks the wheel *g* by drawing its free end between the teeth, as shown clearly in figs. 1, 2. The crank-key *h* is loose to hang on the side of the window-frame when not needed for raising or lowering the sash.

Having thus described my invention, I claim as new, and desire to secure by Letters Patent—

The combination of the bar *a a*, the rack *c c*, and the thumb-screw *d*, the wheel *g* on the plate *e*, and the catch-rod *i*, arranged and operating as and for the purpose specified.

SHERMAN SMITH.
